GAME TARGET PLATE

Filed Aug. 4, 1926

UNITED STATES PATENT OFFICE.

EDWIN W. STODDART, OF NEW YORK, N. Y.

GAME TARGET PLATE.

Application filed August 4, 1926. Serial No. 123,934.

My improvements relate to game plates of a type analogous to that disclosed in Letters Patent No. 1,554,768, issued to me September 22nd, 1925, in conjunction with which ball play is resorted to for scoring purposes in accordance with prescribed rules of an appropriate game,—the object of play being in that case to lodge a ball in a central "bull's-eye" cup, or in any of a series of concentric grooves separated by inclined planes, whereas the object of my present invention is to afford a game board of this class having a centrally located impact-sounding device surrounded by deflective surfaces,— the object of ball play in this case being, primarily, to strike said central "bull's-eye" impact-sounding device, and secondary, to cause an impinging play-ball to bounce off the target at an angle incident to the deflective surface contacted with, all as hereinafter fully set forth.

In the accompanying drawings I illustrate a practical embodiment of the essential features of my invention in a game board of the character designated, although I do not limit myself to the identical form and construction of parts shown herein by way of exemplification, since modifications may be made in minor details, and equivalent mechanical expedients resorted to, with like results, and without departing from the spirit and intent of my invention in this respect.

With this understanding:—

Fig. 1, represents a top view or plan of my new game target plate;

Fig. 2, a transverse central vertical section taken upon plane of line 2—2, Fig. 1;

Fig. 3, a central sectional detail illustrating the effect of the impact of a play ball with the soundable device;

Fig. 4, is a central sectional detail illustrating a modification;

Fig. 5, a view similar to Fig. 4, illustrating still another modification.

My horizontal target T, preferably, although not necessarily, consists of a plate of sheet metal, spun, drawn or otherwise moulded into requisite shape, the distinctive feature in this respect being the formation of the plate with concentric superficial curvilinear grooves or depressions t , t , which are variant in character in that the concavities have no uniform radii, but vary continuously in inclination as related to a common horizontal plane, as will be understood by reference more particularly to Fig. 2, of

the drawings, by which it will be seen that the angle of deflection imparted to an impinging ball will necessarily be dependent on the actual point of superficial contact, the angle of deflection varying continuously from the periphery to the centre of the target. In this connection it may be noted that the play ball P, for use in conjunction with the target T, should be of less diameter and radius than the curvature of the grooves t , t , so as to insure a minimum of contact between surfaces involved in impact.

The "bull's-eye" impact-soundable device B, is preferably, although not necessarily, of the annunciator bell or gong type, with convex upper surface, adapted to deflect an impinging ball P, as indicated in Fig. 3, of the drawings.

Since the balls P, to be used in target play are necessarily of an elastic resilient character, not adapted to promote the resonance to the bell B, I support the latter on a yieldable mount which will allow an impinging ball P, to trip the bell B, temporarily into peripheral contact with an adjacent stationary surface of or on the target T. Thus in Fig. 3, of the drawings, the edge of the tilted bell B, is shown as contacting with an adjacent part of the central groove t' , of the target plate T, whereas in Fig. 4, a contact flange t^2 , is provided for the purpose, a like result being accomplished in Fig. 5, by forming the centre of the target coincident with the bell B, with a flat surface t^3 , in lieu of the central groove t' , shown in the other figures of the drawings.

Obviously, various mechanical expedients may be resorted to in attaining a suitable yieldable retractile mount for the impact-soundable element B, the device shown in the drawings by way of exemplification consisting essentially of a screw bolt b , the head of which functions as a shoulder for retaining contact with the central portion of the bell B, which is perforated to accommodate the shank of said screw bolt, the lower extremity of the latter being secured on the under side of the target plate by a nut n , and a spring s , being interposed between the under side of the bell and the upper side of the target plate, said spring allowing the bell, (and the bolt also if struck direct) to yield to the impact of a play ball, but insuring the return of the bell to normal position as soon as the play ball bounces off.

I have herein shown said retractile means

as consisting of a spiral spring *s*, although I do not limit myself in this particular, since equivalent expedients may be substituted therefor with like results.

5. The rules of the games available in conjunction with my new horizontal target presumably involving scoring for catching the play-ball on its initial bounce after impact, the importance of the variant curvature of 10 the face of the target is obvious in affording an element of uncertainty calling for alertness and skill on the part of a player.

What I claim as my invention and desire to secure by Letters Patent, is:—

15. 1. A horizontal game target comprising a plate the upper surface of which is formed with undulating curves surrounding an impact-soundable device, together with said soundable device, the latter being tiltably mounted.

20. 2. A horizontal game target comprising a plate the upper surface of which is formed with concentric undulating curves surrounding an impact-soundable device, together with said soundable device, the latter being tiltably mounted.

25. 3. A horizontal game target comprising a plate the upper surface of which is formed with variant undulating curves surrounding an impact-soundable device, together with said soundable device, the latter being tiltably mounted.

30. 4. A horizontal game target comprising a plate the upper surface of which is formed with variant undulating concentric curves surrounding an impact-soundable device, together with said soundable device, the latter being tiltably mounted.

35. 5. A horizontal game target comprising a plate the upper surface of which is formed

with undulating curves surrounding an impact-soundable device, together with said soundable device, the latter being tiltably mounted and yieldable means for resiliently supporting the same.

45

6. A horizontal game target comprising a plate the upper surface of which is formed with concentric undulating curves surrounding an impact-soundable device, together with said soundable device, the latter being tiltably mounted and yieldable means for retractably supporting same.

7. A horizontal game target comprising a plate the upper surface of which is formed with variant undulating curves surrounding an impact-soundable device, together with said soundable device, the latter being tiltably mounted and yieldable means for retractably supporting same.

55

8. A horizontal game target comprising a plate the upper surface of which is formed with variant undulating concentric curves surrounding an impact-soundable device, the latter being tiltably mounted together with said soundable device, and yieldable means for retractably supporting same.

65

9. A horizontal game target comprising a plate the upper surface of which is concentrically grooved, and an impact-soundable device centrally tiltably mounted on said grooved plate, substantially in the manner and for the purpose set forth.

70

10. A horizontal game target comprising a plate the upper surface of which is formed with a series of deflective surfaces surrounding an impact-soundable device, together with said soundable device, the latter being tiltably mounted.
